UNITED STATES PATENT OFFICE.

ERLE K. BAKER, OF CHICAGO, ILLINOIS.

MEANS FOR DECORATING ARTICLES.

Application filed December 29, 1924. Serial No. 758,569.

This invention relates to improvements in methods of and means for decorating articles and consists of the matters hereinafter described and more particularly pointed out in 5 the appended claims.

In decorating certain articles, as for instance with paints, enamels, colored varnishes and the like, it is often desired to enhance the appearance of the article by disposing the 10 paint in certain predetermined areas, to produce a design or multi-color effect thereon. Where the said articles are to be decorated in large numbers it is quite difficult to apply the paint or coloring material upon the same relative 15 areas of different articles with uniformity. As an example of the article to be decorated, I have chosen the disc of an automobile wheel. In some instances, it is desired to apply a different colored paint or the like to that 20 part of the disc adjacent to and concentric with the hub opening therein so that the disc will appear ornamental and attractive and minus the dead appearance of a disc having but a single color. Wheel discs of one color 25 having a concentric circular field of another color adjacent the hub opening have been produced by hand with the aid of a brush only. However, this brush and hand method is slow and tedious so that production is indeed 30 limited and the cost is increased in proportion.

One of the objects of the present invention is to provide an improved method of decorating articles such as wheel discs and in the 35 means for carrying out said method, so that uniformity of appearance and speed of operation is readily attained.

A further object of the invention is to provide a method of the kind described whereby 40 production is increased and the cost is materially decreased.

These objects of the invention, together with others as well as the many advantages thereof will more fully appear as I proceed 45 with my specification.

In the drawings,

Fig. 1 is a cross section through a device by means of which my improved method may be readily carried out and illustrates the position 50 of the device upon a wheel disc about to be decorated in accordance with my invention.

Fig. 2 is a top plan view of the parts shown in Fig. 1.

Fig. 3 is an outside face view of a wheel disc 55 after having been decorated in accordance with my invention.

Fig. 4 is a detail sectional view on an enlarged scale of certain of the parts shown in Fig. 1 and which will be more specifically referred to later.

Referring now in detail to that embodiment of the invention illustrated in the accompanying drawings, 1 indicates a wheel disc which it is desired to decorate in accordance with my invention. Ordinarily the disc is 60 either dipped or sprayed to apply a single color to both sides thereof, the invention being particularly advantageous in decorating the disc after its single primary color or coating of paint or enamel has been applied. Said 65 disc has a cambered body 2, the outer portion of which merges into an annular web 3 which web terminates in an annular flange 4, providing a seat for a tire carrying rim not shown. Such a disc is provided at its center 70 with a hub hole 5 and about the same are disposed arcuately spaced, flanged openings 6 for the bolts by means of which the finished wheel disc is attached to the usual hub flange 75 of a wheel.

7 indicates an open top and bottom bowl-shaped guide which is circular in plan and which defines that area on the outer face of the disc to which a contrasting color is to be applied. As herein shown, said guide defines 80 an area at the center of the disc and concentric with the hub opening therein and is of a diameter sufficient to include the arcuately spaced bolt openings 6 before referred to. To readily centralize or position said guide, means 85 are provided to engage parts of said disc remote from said hub hole and so that the guide may be used in connection with discs of different sizes, said means are made adjustable. To 90 this end, I provide on the outside of said bowl-shaped guide a plurality of arcuately spaced bosses 8 having threaded openings 9 therein disposed radially with respect to said guide. Said openings do not extend through the wall of said guide but terminate short of 95 the inner surface thereof as shown in Fig. 4 to leave said inner surface smooth and uninterrupted. Threaded into each opening is a 100 radially disposed arm or rod 10 which may be adjusted inwardly or outwardly with respect to the guide and then locked in the adjusted position by means of a jamb nut 11. Said arms, the outer ends of 105 which are adapted to engage with fixed parts of the article or disc being decorated, the 110 guide may be accurately positioned with respect to the predetermined area to receive the

second coat of paint or the like, the bottom edge of the guide sharply defining said area.

After the arms or rods 10 have been properly adjusted, the device as a whole is placed 5 within a disc 1 as shown in Figs. 1 and 2 with the outer ends of the arms engaging the web portion 3 of the disc. This positions the guide centrally of the disc to define an area about and concentric with the hub opening 5. 10 The second coat of paint or coloring material is then applied to said area either by means of a brush or a spraying device. In Fig. 1 I have conventionally shown the use of a spraying device 12 by means of which said 15 coat is applied to said area. When said area has thus been covered, the device as a whole may be removed from the disc which is then permitted to dry with the result that a disc having a two color coat is provided. In Fig. 20 3, I have shown a face view of the finished disc with a centrally disposed spot or area 13 of one color arranged on a field 14 of another color. This two color arrangement on a wheel disc makes it more attractive in appearance and relieves the sameness or deadness of a one color disc.

The inside of the guide may be wiped or cleaned off from time to time as it is deemed advisable to prevent the paint or other coloring used from "curtaining" or flowing about the bottom edge of the guide when removed, which would make the outline of the central colored area 14 irregular. In this manner the outline of the said area is maintained sharp and clean. After one disc is finished, the device is removed therefrom and applied to another and the paint or coloring applied to said area as before mentioned, the engagement of the arms 10 with said part 25 30 35 40 of the disc accurately positioning the guide

with respect thereto each and every time it is applied to another disc so that absolute uniformity of production is insured.

My improved method is rapid and accurate and the guide is simple and efficient for its 45 intended purpose.

While in describing my invention, I have referred to certain details of construction and arrangement of parts as well as the steps by means of which it is carried out, the same is 50 to be taken as by way of illustration only and I do not wish to limit myself thereto except as may be pointed out in the appended claims.

I claim as my invention:

1. A device of the kind described embodying therein a guide member and a plurality of radially disposed arms adapted to engage parts of a wheel disc at points spaced from the center thereof. 55 60

2. A device of the kind described embodying therein, a guide member and a plurality of radially disposed, adjustable arms adapted to engage parts of a wheel disc at points spaced from the center thereof. 65 70

3. A device of the kind described embodying therein, a tubular shaped guide member open at its top and bottom ends and a plurality of arms extending radially outward from said guide member. 75 80

4. A device of the kind described embodying therein a tubular shaped guide member wider at one end than the other and open at both ends, and a plurality of radially outward arms on said guide member, longitudinally adjustable with respect thereto. 85 90

In testimony whereof, I have hereunto set my hand, this 15th day of December, 1924.

ERLE K. BAKER.
